UNITED STATES PATENT OFFICE.

RALPH HAMILTON BEACH, OF NEW YORK, N. Y.

GREASE-CUP.

1,283,628.

Specification of Letters Patent.

Patented Nov. 5, 1918.

Application filed November 12, 1914. Serial No. 871,646.

To all whom it may concern:

Be it known that I, RALPH HAMILTON BEACH, a citizen of the United States of America, residing at the Hotel Majestic, 5 72nd street and Central Park West, New York city, in the county and State of New York, U. S. A., electrical engineer, have invented certain new and useful Improvements in Grease-Cups, of which the following is a specification.

This invention relates to improvements in lubricators of the grease cup type, and aims to provide improvements therein.

In the present invention a grease cup is provided which may be filled without the removal or separation of the parts. The invention further provides a grease cup which may be readily filled, in which the liability of introducing dust into the cup is minimized, and which, when closed, acts to securely retain the grease, so that the grease will not escape except through the orifice leading to the part to be lubricated.

The invention further provides a grease cup which is simply constructed, and which can be cheaply manufactured.

Other features of importance will be pointed out hereinafter.

Embodiments of the invention are illustrated in the accompanying drawings, wherein—

Figure 1 illustrates the grease cup in elevation.

Fig. 2 shows the grease cup in vertical section.

Fig. 3 shows the grease cup in elevation, with parts in section, the grease cup being in the position for filling.

Fig. 4 is a horizontal section of the grease cup on the line 4—4, Fig. 2.

Fig. 5 illustrates a further embodiment, the cup being shown in vertical section.

Fig. 6 is a section on the line 6—6, Fig. 5.

Fig. 7 illustrates a detail of construction applicable to any of the embodiments of the invention.

Referring to the drawings, A designates the cup proper, having a feed orifice a and one or more filling orifices a'. B designates 50 a cover. C designates a follower adapted to fit closely within the cup A, and adapted to be traveled or moved by suitable means, such as the rod D journaled in the cover and having threaded engagement with the follower C. A pin d fitting partially in a groove cut in the rod, may be provided for

preventing longitudinal movement of the rod D in the cover. A spring E adapted to bear upon the follower may be provided between the cover B and the follower. The 60 cover B and cup A have interengaging means F, preferably of the continuous type, such as screw threads. The cover B also has a skirt or sleeve b, adapted to telescope the cup A, and the cup A is provided with a seat 65 or shoulder a², against which a part, such as the edge b', of the skirt is adapted to fit. The interengaging surfaces of the parts a² and b' are so formed as to make a close contact, forming a tight closure against escape 70 of grease through the filling orifice a', under pressure of the follower C.

The follower C is of such a thickness, or the follower is so limited in its upward or outward movement, or both, that the cover 75 B may be lifted, by unscrewing or otherwise, in such manner that the strip b may expose the filling orifice, without involving a separation or removal of the follower C from the cup, see Fig. 3. This feature is one of importance, inasmuch as in a construction, such as the present, where the follower fits closely within the interior of the cup, it is a difficult matter to reinsert the follower into the cup, particularly when the follower is in its 85 withdrawn position, as shown in Fig. 2 or 3.

When the interengaging means F are in the form of screw threads, the screw threads are preferably of such a length that the cover may be turned in such manner that 90 the skirt b will expose the filling orifice a' without the interengaging means becoming separated.

When the oil cup is located in comparatively inaccessible places, such as in certain 95 parts of automobiles, it is sometimes difficult, in filling the grease cup, to have the filling orifice opposite the point of most convenient access. In order to overcome this difficulty, the grease cup may be provided 100 with a plurality of filling orifices a', as shown in Figs. 5 and 6. In addition, a ring G, having preferably a single orifice g therein, may be provided to surround the row of filling orifices. The ring G is turned to a 105 position to bring the orifice g thereof into register with the filling orifice a' most convenient of access.

The skirt b is preferably arranged on the outside of the cup, and closes the filling 110 opening or openings, when the parts are in closed position, as shown in Fig. 2.

If desired, a packing H, as shown in Fig. 7, may be provided between the parts b' and a² of the cover and cup respectively.

The invention is capable of receiving a variety of mechanical expressions, and is not confined to the particular embodiments illustrated and described.

What is claimed is:—

1. A lubricator, comprising a cup adapted to contain grease, a filling orifice in said cup, a cover having a skirt adapted to cover said filling orifice, said cup having a seat and said skirt having a part adapted to contact with said seat to form a grease-tight closure, and a follower, said follower and cup being adapted to remain in conjunction when said cover is raised to an extent sufficient to uncover said filling orifice.

2. A lubricator, comprising a cup adapted to contain grease, a filling orifice in said cup, a cover having a skirt adapted to cover said filling orifice, interengaging means between said cover and cup, said cup having a seat and said skirt having a part adapted to contact with said seat to form a grease-tight closure, and a follower, said follower being adapted to remain in said cup when said cover is raised to an extent sufficient to uncover said filling orifice, and said interengaging means being adapted to remain interengaged when said cover is raised to an extent sufficient to uncover said filling orifice.

Copies of this patent may be obtained for five cents each, by addressing the "Commissioner of Patents, Washington, D. C."

3. A lubricator, comprising a cup adapted to contain grease, a plurality of filling orifices on the side thereof, and a ring surrounding said orifices, said ring having an orifice therein adapted to register with one or another of said filling orifices.

4. A lubricator, comprising a cup adapted to contain grease, a plurality of filling orifices therein, a ring surrounding said orifices, said ring having an orifice therein adapted to register with one of said filling orifices, and a cover, said cover having a skirt adapted to contact with a part of said cup and form a grease-tight closure.

5. A lubricator, comprising a cup adapted to contain grease, a filling orifice in said cup, a cover having a skirt adapted to cover said filling orifice, said cup having a seat and said skirt having a part adapted to contact with said seat to form a grease-tight closure, a follower, means journaled in said cover adapted to actuate said follower, said follower and cup being adapted to remain in conjunction when said cover is raised to an extent sufficient to uncover said filling orifice.

In witness whereof, I have hereunto signed my name in the presence of two subscribing witnesses.

RALPH HAMILTON BEACH.
